Lucas J. Knowles

United States Patent Office.

LUCIUS J. KNOWLES, OF WARREN, MASSACHUSETTS.

Letters Patent No. 97,095, dated November 23, 1869.

IMPROVEMENT IN MACHINES FOR WINDING THREAD ON BOBBINS, &c.

The Schedule referred to in these Letters Patent and making part of the same.

Know all men by these presents:

That I, LUCIUS J. KNOWLES, of Warren, county of Worcester, and Commonwealth of Massachusetts, have invented certain new and useful Improvements in Quillers; and I do hereby declare that the following is a full, clear, and exact description of the same, reference being had to the accompanying drawings, forming a part of this specification, in which—

Figure 1 represents a front view of my improved quiller;

Figure 2 represents a plan view of my improved quiller; and

Figure 3 represents a section of the shipping-device, on line A B, fig. 2.

To enable those skilled in the art to which my invention belongs, to make and use the same, I will proceed to describe it more in detail.

In the drawings—

The part indicated by the letter A is the driving-shaft, furnished with a tight pulley, B, and loose pulley, C, to which the power is applied by means of a belt.

The shaft A is supported and turns in bearings *a*, on the top frame D, said top frame being attached to the main frame E by a screw, *b*, in such a manner that the parts can be adjusted to a correct relative position.

The driving-shaft A is provided, at its right-hand end, with a balance-wheel, *e*, and at its left-hand end, with a spindle, *d*, (shown in the drawings by dotted lines,) to receive the quill or bobbin F, upon which the thread is to be wound.

A worm or screw, A', is cut on the shaft, and engages and operates a gear, G, to the front side of which is secured the cam H, that moves the winding-guide I.

The cam H is made of heart-form, and is provided with two slots, one of which fits on to the hub of gear G, while through the other is passed the clamping-screw *f*, by means of which the cam H is securely fastened to one arm of the gear G. By this mode of construction, the cam H can readily be adjusted to wind bobbins or caps of different lengths.

The winding-guide I is provided with a pin, *h*, which rests against and is moved by the face of cam H; and at its lower end it is pivoted on the stud J, said stud being secured in a slotted hanger, *i*, that projects downward from the main frame E.

The winding-guide I is made in the form of a bell-crank, as shown in fig. 1, and a weight, K, is hung on the projecting part *g*, to keep the stud *h* in contact with the cam H.

At the top of the winding-guide I, is a glass tip or curl *m*, for holding and guiding the thread. The

glass curl *m* is cemented into an opening, formed in the top end of the metallic arm L.

By the use of glass for the curl *m*, there is much less friction on the thread than there would be with any other material, and the thread is not liable to become injured or broken.

By means of the slot in the hanger *i*, the stud J may be moved, to adjust the winding-guide I to any desired position.

The bobbin F is held in place on the spindle *d* by a bolt, *k*, arranged in the upper end of an arm, L, which is pivoted to the main frame E.

The point of the bolt is turned, for a short distance, to the same diameter as the spindle *d*, so that it will fit into the end of the bobbin F, while it can easily be drawn out, by swinging back the arm L, when the bobbin is to be removed from the spindle.

The bolt *k* is secured to the arm L, and made adjustable by a set-screw, *l*.

The bobbin F is prevented from turning on the spindle *d* by a pin, *n*, in the end of the shaft A, that fits into a hole in the head of the bobbin.

A disk, M, is formed at the lower end of arm L, through which passes the pivot-screw *o*, that screws into the frame E, and a weight, N, is attached to a projecting portion of said disk, at *p*, which tends to press the bolt *k* against the bobbin F.

A pin, *q*, projecting from the frame E, is arranged in a recess in the edge of the disk M, to prevent the arm L from swinging too far in either direction.

In rear of the main shaft A, and turning in bearings S, on the frame D, is a shaft, P; upon which is cut, in rear of the pulleys B and C, a screw-thread, *t*, and upon which is arranged the shipper R, the form of which is fully indicated in the drawings.

An opening is formed through the shipper R, having at its top a screw-thread, to fit the thread *t* on the shaft P, while the lower half of said opening is large enough to clear the shaft, so that the shipper may be raised and moved along the shaft when desired; but when not so raised, it can only be moved by the screw on shaft P.

To the end of shaft P, in the rear of the bobbin F, is secured a leather roll, T, which is large enough to strike the thread when the bobbin is full; the operation being as follows:

The bolt *k* is drawn back, and an empty bobbin or cop-tube is placed upon the spindle *d*, the thread is passed through the curl *m*, and attached to the bobbin. Then, by raising the shipper R, and moving it to the left, the belt is carried on to the pulley B, which sets the machine in motion.

The winding-guide I is caused, by the movement of cam H, to swing, carrying the curl *m*, which holds

the thread, back and forth in front of the bobbin, upon which the thread is wound, in a very even and regular manner.

When the bobbin is filled to the proper size, the thread presses against the face of the leather roll T, which is caused, by friction thereon, to revolve the shaft P, and the action of the screw upon the shipper R carries the belt to the loose pulley C, thereby stopping the motion of the machine, when the filled bobbin, or cop, as the case may be, can be removed, and the operation repeated.

The main frame E is provided with a backward-projecting flange, V, which is fastened to the plate W by the bolt w, and the plate W is screwed to the frame of the loom, on which the quiller is to be used.

By this mode of construction, the quiller can be used on a right or left-hand machine, without any variation of the castings, or any alterations of the parts, except moving the plate W to the position shown in dotted lines, fig. 3.

The last feature is quite important, since it obviates not only the necessity of making the quillers right and left-handed, as they have been made heretofore, but prevents the delay and annoyance which have heretofore resulted, from the omission of parties ordering machines to state whether they were to be used on a right or left-hand loom.

By the use of the balance-wheel e, the quill or bobbin-spindle is prevented from starting as suddenly as it otherwise would, by the shifting of the belt, and consequently there is less breaking of the thread during the operation of quilling.

The balance-wheel also serves as a hand-wheel, by means of which the operator can stop the spindle readily, or control its motion at pleasure.

Having described my improved quiller,

What I claim therein as new, and of my invention, and desire to secure by Letters Patent, is—

1. The combination and relative arrangement, with the screw-shaft P and pulleys B and C, of the shipper R and wheel T, substantially as and for the purposes set forth.

2. The combination, with the adjustable cam H, of the vibratory winding-guide I, its pivot J, and slotted hanger, in which such pivot is held and adjusted, substantially as and for the purposes set forth.

3. The combination of the frame E and weighted arm L, having the recessed disk M, with the pin q, said parts being constructed and arranged substantially as and for the purposes set forth.

4. The combination, with the frame E, of the projection V and forked arm W, hinged or pivoted to said projection, so as to admit of the turning of the quiller-frame, according as it is used upon a right or left-handed loom, substantially as and for the purposes set forth.

5. A quiller, the parts of which are constructed, combined, and arranged, in relation to each other, as shown in the drawings, and above described.

LUCIUS J. KNOWLES.
